UNITED STATES PATENT OFFICE.

MILDRED C. SCHMOLZE, OF NEW YORK, N. Y., ASSIGNOR TO FRANKLIN SIMON & CO., OF NEW YORK, N. Y., A CORPORATION OF NEW YORK.

DESIGN FOR A CHILD'S DRESS.

Application filed January 15, 1925. Serial No. 12,063. Term of patent 3½ years.

To all whom it may concern:

Be it known that I, MILDRED C. SCHMOLZE, a citizen of the United States, and a resident of the city of New York, borough of Manhattan, in the county and State of New York, have invented a new, original, and ornamental Design for Child's Dress, of which the following is a specification, reference being had to the accompanying drawing, forming part thereof, wherein the dress is distinguished by several large plaits in the front of the skirt while the blouse is distinguished par-

ticularly by the ornamental pockets having a color scheme matching with the ornamental color scheme at the lower ends of the tie which extends from beneath a collar and tied at a point adjacent the lower end of the neck opening.

The figure is a front view of a child's dress, showing my new design.

I claim:

The ornamental design for a child's dress, substantially as shown and described.

MILDRED C. SCHMOLZE.
